UNITED STATES PATENT OFFICE.

ALBERT F. PRESTON, OF LYNN, MASSACHUSETTS, ASSIGNOR TO THE PRESTON MACHINE COMPANY, OF PORTLAND, MAINE.

MACHINE FOR STRETCHING UPERS OF BOOTS OR SHOES.

SPECIFICATION forming part of Letters Patent No. 455,024, dated June 30, 1891.

Application filed December 30, 1889. Renewed November 28, 1890. Serial No. 372,898. (No model.)

To all whom it may concern:

Be it known that I, ALBERT F. PRESTON, of Lynn, in the county of Essex and State of Massachusetts, have invented certain new and useful Improvements in Machines for Stretching Uppers of Boots or Shoes, of which the following is a full, clear, and exact description.

This invention relates to a machine for stretching uppers of boots or shoes, more particularly at the shank, preparatory to their being lasted, for the easier and quicker lasting and the better fit of the upper at the shank; and the invention consists of two sets of rolls, each roll of each set secured to a separate shaft and arranged to revolve in a suitable support in connection with the other rolls, and constructed and arranged for operation substantially as hereinafter fully described; and the invention also consists of the construction and arrangement of other parts in connection therewith, all substantially as hereinafter fully described.

In the accompanying sheets of drawings is illustrated a machine constructed in accordance with this invention, in which—

Figure 1 is a side view of the machine on a standard ready for operation. Fig. 2 is a front view. Fig. 3 is a rear view. Fig. 4 is a plan view. Fig. 5 is a plan view below section-line 5 5, Fig. 6. Fig. 6 is a vertical longitudinal section on line 6 6, Fig. 2. Fig. 7 is a vertical cross-section on line 7 7, Fig. 4. Fig. 8 is a detail side view of an upper to be hereinafter referred to. Fig. 9 is a horizontal section above the upper rolls, and showing the rolls and their shafts in plan view.

The views Figs. 2 to 7, both inclusive, and Fig. 9, are enlarged, and relate to the operating parts of the machine, supported by the frame-work secured to the top of the standard.

In the drawings, A represents a standard having feet B, having secured on its upper end in any suitable manner a frame-work C, on which are supported the various operating parts of the present invention.

D and E are two rolls, one D above the other E, and which make one set and might be called the "feeding-rolls," and F G are two other rolls at the side of the first two rolls,

one F above the other G, making the other set, and which might be called the "operating-rolls," although both sets operate together. The four rolls project from the front of the frame-work C, and each is secured to and on the front end of a separate horizontal shaft H, J, K, and L, respectively. The shaft J to roll E turns in bearing-blocks M N, one M at the front and the other N at the rear, and each block has a horizontal side-projecting pin a, which pass through sockets b, respectively, in the side frame d, each having a screw-thread on its outer end outside of the frame to receive a screw-nut e, by which the two bearing-blocks M N are secured and held firmly in place against the side frame for the support of the shaft J. The shaft H of the roll D, above the roll E, has its rear block P provided with a horizontally side-projecting pin f, which passes through a socket c' in the side frame d, and is secured to the side frame by a screw-nut g on the outside of the frame in a like manner to the block N, but so that the block can swivel by its pin in its socket. The shaft L of the roll G is arranged to turn in bearing-blocks Q R, like the blocks M N to the shaft J of roll E; but their respective horizontal side-projecting pins h are on the opposite side and are secured in sockets m, respectively, in the other side frame n by screw-nuts r. The shaft K of the roll F has a rear bearing-block S, like the bearing-block P of the shaft H of roll D, its horizontal side-projecting pin t being in a socket d'' in the side frame n and secured by screw-nut u, but free enough to swivel in its bearing-socket like the bearing-block P for the shaft H. The upper shafts K H turn in front bearing-blocks T U, respectively, which are disposed between the two side frames n d, and between these bearing-blocks and the front bearing-blocks of the lower shafts is a flat vertical strip V, which extends down into an open slot z in the bottom cross-piece U of the frame, and is prevented from escape by a bar v, secured to the front of the bottom piece by screws w over the slot, the strip being arranged to move freely up and down between the bearing-blocks and in the open slot.

Pivoted on a cross-pin y of the strip V are blocks a' a', one on each side, the pin being

secured in the strip and projecting each side sufficiently to receive the blocks, and on which pin the blocks swivel. The adjacent corners of the four front bearing-blocks are cut away 5 sufficiently, as shown in Figs. 3 and 7, to allow room for the blocks and for the upper front bearing-blocks T U to rest thereon, as shown more particularly in Fig. 7. The upper end of this strip is pivoted at b' between 10 the forked end c' of a horizontal lever Y, pivoted to the upper front bar A' at d', the forked end fitting loosely in a vertical open slot e' in the under and front side of the bar.

15 B' B' are pins disposed in vertical sockets f' f' in the cross-bar A' and resting on the upper bearing-blocks T U and projecting a short distance above the bar for the free ends of flat springs C', respectively, to bear there- 20 on, the middle portion of each spring bearing up against the lower side g' of a cross-bar D' of the frame and each spring being secured by its other or rear end h' by a thumb-screw E', screwing through and bearing against the 25 upper side of the rear cross-bar F' of the frame. As either thumb-screw E' is turned down, it raises its end of its respective spring, and by the confinement of the spring under the cross-bar D' the free end of the spring 30 will be caused to bear the more firmly on its vertical pin B', and thus upon its bearing-block T or U of the upper rolls F D to hold the rolls to their work with the degree of pressure desired, and turning either thumb- 35 screw up correspondingly relieves such pressure. The other end of the lever Y is connected to a rod m', which passes freely down through an opening n' in an arm G' of the standard, and is connected by its lower end 40 to the rear end of a treadle H', pivoted at q' to the standard. On the rod m', between the arm G' and a collar J', secured on the rod by a set-screw r', is a spiral spring t', which by its tension pushes down the rod, and with 45 it the rear end of the lever, lifting by its connecting-strip V the upper rolls from the lower rolls against their springs C', their shafts swinging on their rear bearing-block pins, (shown in Fig. 9,) which is the normal posi- 50 tions of the upper rolls. Pressing down the treadle raises the lever and allows the roll springs C' to freely act upon the upper rolls to press them down upon the lower rolls, which remain so long as the treadle is held 55 down; but when allowed to rise the spring t' to the treadle acts to raise the upper rolls at their front ends, as shown, into their normal positions. The shaft H of the upper roll D ex- 60 tends back of the rear part of the frame and has a gear-wheel J'', which engages with a gear- wheel K' of half its diameter on the shaft L of the lower roll G, diagonally opposite thereto. Secured to the shaft L beyond the gear-wheel K' is a miter gear-wheel L', which engages 65 with a miter gear-wheel M', secured on a short horizontal shaft N' at right angles thereto, and arranged to turn in bearings in the parts

P' of the frame, and having a pulley Q' secured to its outer end for operation thereof. The shaft H of the roll D has a bevel gear-wheel R', which engages with a bevel gear-wheel S' on the shaft J of the roll E, and the shaft K of the roll F has a bevel gear-wheel T', which engages with a bevel gear-wheel U' on the shaft L of roll G, these gear-wheels being all of the same diameter. By turning the shaft N' the shaft of the lower roll F is turned, which by the gear-wheel K' turns the upper roll-shaft H diagonally opposite thereto, and by the intermediate gear-wheels on the roll-shafts the other two rolls are correspondingly revolved.

The upper to be stretched is placed by its proper edge at one end in and between the rolls from the right, as shown in dotted lines 85 in Fig. 4, and then the treadle is pressed down, which raises the lever Y and allows the upper set of rolls to rest and press upon the upper placed between them. The pulley is then re- 90 volved in any suitable manner, which causes all the rolls to turn in the direction of the arrows, Fig. 2, which feeds the upper through or between the upper and lower rolls, and as it is so fed or moved the portion of the upper that is pressed between the rolls is stretched, 95 and from the relation of the diameters of the last two or operating rolls F G to the diameters of the first two or feeding rolls D E and the relative differences of their diameters from their ends backward the upper will be 100 stretched more at the edge and gradually less therefrom toward the central portion, and also from the central point at the edge toward each end of the stretched portion, which gives the necessary and required stretch to the upper. 105

In the present feeding-machine the rolls D E are of larger diameter at their outer ends and decrease in diameter or taper from such ends backward equally, and the operating-rolls F G are smaller in diameter at their outer ends and increase in diameter back therefrom equally, which increase in diameters corresponds to the decrease of the diameters of the other or feeding rolls. Because of the taper of the several rolls and to bring 110 the faces or operating-surfaces of the rolls contiguous and parallel with each other, as shown, for the better operation of the machine, the central axial lines of their respective shafts are arranged diagonally in relation to 115 each other, as shown, except that the central axial lines of the two shafts H L, diagonally opposite to each other, are parallel with each other.

In a practical operating-machine the diameter of each feeding-roll D E at the line u', which is one-quarter of an inch from the end, is one and three-eighths ($1\frac{3}{8}$) of an inch, and from this line each decreases in diameter one-eighth ($\frac{1}{8}$) of an inch to each inch in 130 length, and the diameter of the operating-rolls F G at the line v', which line corresponds to and is the same vertical plane with the line u' on the feeding-rolls, is eleven-six-

teenths (11) of an inch, or just one-half of the diameter of the feed-rolls, and from this line backward the diameter of each of these rolls increases one-eighth (1/8) of an inch to each 5 one inch in length, and the diameters and increase of diameters of the operating-rolls in relation to the diameters and decrease of diameters of the feeding-rolls, as the piece of material of which the upper is made is 10 fed through and between the upper and lower rolls, is what gives the stretch to the upper more at the edge and decreasing centrally back therefrom and lengthwise, as is desired for the better lasting of the upper.

15 Although the operating-rolls at the lines v' are one-half the diameter of the feeding-rolls at the lines w' , the surfaces of the operating-rolls at such lines travel with the same speed that the surfaces of the feeding-rolls at such 20 lines do, for the reason that the gear-wheel K' of operating-roll shaft L is half the diameter of the gear-wheel J'' of the feeding-roll shaft H . Therefore the leather of the upper at such line is not stretched; but backward 25 from these lines on the rolls the operating-rolls increase in diameter and the feeding-rolls correspondingly decrease in diameter, and accordingly the surfaces of the operating-rolls increase in speed and the surfaces 30 of the feeding-rolls decrease in speed, which correspondingly pulls and stretches the material of the upper, for in their operation the operating-rolls tend to pull the material through faster from their front ends to their 35 rear ends, and at the same time the feeding-rolls tend to correspondingly hold back upon the material from the front ends to their rear ends, and correspondingly the material will be stretched more at the edge of the upper 40 than back therefrom, and such stretch is illustrated in Fig. 8, which is a side view of an upper, in which w' is the edge where stretched, and y' is a line representing where practically all the stretch ceases, the stretch 45 being more at the central point z' on the edge and diminishing gradually toward the line y' radially, as it were, and to the extreme points $a'' b''$. The pull upon and the stretch of the material as it passes between 50 the rolls is such that the material will pass out from and between the rolls when it arrives at the point a'' and practically only stretch the upper between the curve-line y' and its edge w' .

55 In addition to the operating-rolls acting to stretch the material they also roll and press the material, so that when it leaves the rolls in its stretched condition it will practically remain so, and not contract or return to its 60 original condition.

In lieu of making the several rolls of the differences in diameters and increase and decrease of speeds in the proportions herein stated, they can be varied as desired; but in 65 such variations the increase of speed of the last two rolls from their outer ends inwardly relatively to the decrease of speed of the feed-

ing-rolls from their outer ends inwardly must be maintained in a more or less degree, according as the upper is required to be 70 stretched more or less at the edge—as, for instance, the feeding-rolls can be straight or parallel with each other; but in such case the operating-rolls should increase in diameter backward from their outer ends and correspondingly quicker. It is preferable, however, to have the feed-rolls diminish in diameter from their outer ends, as in feeding the piece of material between the rolls it will be moved because of such decrease of diameters 75 in a direction to give the peculiar stretch, and which is described and shown, needed to the shank of the upper.

Although the first two rolls are designated as "feeding-rolls," they also operate in stretching the material in connection with the others, in that they not only hold it for the operating-rolls to pull and stretch it, but also tend by their decrease of diameters to retard its delivery to the operating-rolls correspondingly to such decrease of diameter, and thus insure the better and fuller stretch of the material.

To assist in placing and guiding the upper in between the rolls, a plate W' , secured to 95 the side of the frame by the screw-nut e , has an open horizontal slot d'' , which is in the same horizontal plane of the space between the upper and lower feed-rolls.

To insure that the material being stretched 100 shall not slip, the rolls are corrugated or grooved longitudinally, as shown at $f'' g''$, the lower rolls being corrugated the full length, but the upper rolls only being corrugated part way, as shown, for the reason that 105 as the upper is run through the machine with its face side uppermost it will not answer to have the upper rolls corrugated too far forward, so as not to extend over and back from the edge sufficient to injure the face of the 110 upper that might show after the boot is finished. The part nearest the edge being taken up in securing the soles to the upper, it will do no harm to have the corrugations bear upon such part.

115 The rolls can be made to operate at their extreme outer ends, and not back therefrom at the lines w' and v' , as stated; but in having the operating-line back from the ends the rolls between such lines and their outer ends 120 should preferably be straight, having no taper in either direction. The rolls in the present instance are preferably made of a collar or sleeve shape and made to fit on the ends of their respective shafts and abut against the 125 front part of the frame and are secured by transverse strips h'' and screws m'' , as shown, although they can be made integral with the shafts or in any suitable manner, and also can be made of any suitable material and corrugated or grooved in any suitable manner; also, the various parts of the machine can be made 130 of any suitable metal.

The rolls can be changed more or less as to

their tapering or varying of diameter, as stated before; but it is essential that either the feeding-rolls or the operating-rolls must be tapering in order to produce the stretch of the upper desired, although it is preferable to have both sets tapering and about as described. The shaft K has a plate R' secured on its end by a screw n'', bearing against the side of its front block S, securing the shaft to the block and preventing its detachment therefrom, the other shafts being held by their end gear-wheels.

Having thus described my invention, what I claim is—

- 15 1. The combination of two sets of rolls, each roll of each set secured to a separate shaft arranged to revolve in a suitable support in connection with the shafts of the other rolls, the rolls of one set being tapering, for the purpose specified.
- 20 2. The combination of two sets of rolls, each roll of each set being secured to a separate shaft arranged to revolve in a suitable support in connection with the shafts of the other rolls, the rolls of one set tapering in one direction and the rolls of the other set tapering in the other or reverse direction, for the purpose specified.
- 25 3. The combination of two sets of rolls, each roll of each set being secured to a separate shaft arranged to revolve in a suitable support in connection with the shafts of the other rolls, the rear bearing-blocks for the shafts of the upper rolls of each set of rolls being pivoted to their support, and the front bearing-blocks of said shafts connected to a lever for raising said rolls, for the purpose specified.

4. The combination of two sets of rolls, each roll of each set secured to a separate shaft arranged to revolve in a suitable support, the opposite diagonal shafts of the two sets of rolls being connected to each other by gear-wheels and the lower shaft of each set of rolls being connected to the upper shaft of its set of rolls by gear-wheels, for the purpose specified.

5. The combination of two sets of rolls, each roll of each set being secured to a separate shaft arranged to revolve in a suitable support in connection with the shafts of the other rolls, the rear bearing-blocks for the shafts of the upper rolls of each set of rolls being pivoted to their support, and a spring C' to each upper roll of each set, for the purpose specified.

6. The combination of two sets of rolls, each roll of each set being secured to a separate shaft arranged to revolve in a suitable support in connection with the shafts of the other rolls, the rear bearing-blocks for the shafts of the upper rolls of each set of rolls being pivoted to their support, the front bearing-blocks of the set of rolls connected to a lever Y by a strip V, arranged between the front bearing-blocks of the two sets of rolls.

In testimony whereof I have hereunto set my hand in the presence of two subscribing witnesses.

ALBERT F. PRESTON.
